JACOB RAMACHER, OF DELLBRÜCK, BEZ., COLOGNE, GERMANY, ASSIGNOR TO WALTER GARTNER, OF HAMBURG, GERMANY.

FURNACE FOR STEAM-GENERATORS.

1,077,203.

Specification of Letters Patent.

Patented Oct. 28, 1913.

Application filed April 29, 1912. Serial No. 693,852.

To all whom it may concern:

Be it known that I, JACOB RAMACHER, a subject of the Emperor of Germany, residing at Dellbrück, Bez., Cologne, Germany, have invented certain new and useful Improvements in Furnaces for Steam-Generators, of which the following is a specification.

This invention relates to furnaces for steam generators of the type in which the fuel is fed laterally to the fire grate through hoppers arranged on either side of the grate. In such furnaces the fuel is partially coked before being delivered to the grate where combustion takes place and fire brick cheeks or partitions have hitherto been provided above the grate on either side thereof to restrict the passages through which the fuel is fed and by being heated, serving to assist in the coking of the fuel before it reaches the grate. Such partitions or cheeks, which hitherto have been employed in connection with fire tube steam generators, are found in practice to become overheated, with the result that the fuel is coked to a greater extent than is desirable, and the object of the present invention is to provide means whereby the rate or degree of coking can be modified to suit requirements, provision being also made to prevent those portions of the partitions which are in contact with the fuel on its way to the grate from being overheated.

According to this invention two sets of air chambers or conduits are provided on each side of the grate, one set of chambers being formed in the fire proof partitions and supplied with cold air, not previously heated in any way, to cool the back of each partition where the latter is in contact with the fuel and so prevent coking taking place beyond the desired extent, the other set of air conduits being formed below the fuel passages and serving to supply warm air thereto for the purpose of assisting the coking, dampers being provided to regulate the amount of warm air thus admitted. After cooling the back of the fire-proof partitions the air is led through further passages into the combustion chamber where it arrives in a warm state and assists combustion in the known manner, the primary object of the cooling chambers communicating with the combustion chamber being to induce a further flow of cold air through the cooling

chambers to retard or prevent coking beyond the required point in the fuel chambers.

The main supply of fuel at each side of the furnace is contained in a separate hopper the lower end of which is closed by a valve which can be intermittently opened in the known manner to allow the fuel to fall into the coking chamber and fuel supply passages.

In the accompanying drawings which show one form of air cooled partition according to this invention applied by way of example to a steam generator of the known central flue type, Figure 1 is a transverse vertical section through a steam generator furnace modified in accordance with the present invention. Fig. 2 is a longitudinal vertical section through the same, and Fig. 3 is a transverse vertical section through a water-tube steam generator, also according to this invention. Figs. 4 and 5 are detail views, on an enlarged scale, of a form of damper for regulating the supply of air to the fuel.

The invention is illustrated in Figs. 1 and 2 as applied to a steam generator of the known type comprising a curved grate A disposed directly below an opening B' in the boiler shell B which is provided with a longitudinal flue C. The grate is connected in the known manner by inclined passages D with fuel hoppers D' disposed on each side of the shell and the flue C is connected to the shell by a ring E of angle section.

On the underside of the boiler shell are arranged refractory cheeks or partitions F which, in the known manner, restrict the passage through which the fuel is fed to the grate and in this construction serve to protect the rivets which connect the ring E to the boiler shell. The fuel is delivered to the grate A behind the partition F being coked to a greater or less extent before it reaches the grate. In each partition F are formed one or more longitudinal air passages, one passage H being arranged at the back of the partition and formed of cast iron or like material let into the partition. This passage H is connected by one or more transverse conduits H² with a second approximately central air passage H' also formed of cast iron and having one or more horizontal openings F'. The openings F' extend to the combustion chamber and so allow air from outside the furnace to pass

through the passages H, H², H' to the space above the grate where it assists in combustion in the usual way. By forming the back of each partition hollow as above described and by so inducing a constant flow of cold air to the furnace, not only is the latter supplied with warm combustion air as is well known but the back portion of each partition is maintained at a low temperature thus preventing the fuel in contact therewith on its way to the grate, being prematurely coked owing to the heat of the partitions or by the fire on the grate working upward.

The main supply of fuel in the hoppers D' is allowed to fall into the fuel passages D by opening a valve G of the known type. The fuel then descends between the back of the partitions F and an inclined wall J to the grate. On the lower part of the wall J and between it and the grate is formed a longitudinal passage K to which air is supplied from below. The air from this passage issues through elongated tapered openings K' into the coking chambers on either side of the grate and dampers K² are provided which enable the supply of air to be regulated. In this way the amount of air which passes through the coked fuel can be adjusted and thus the degree and rate at which coking takes place can be regulated.

Fig. 3 shows the invention applied to a water tube boiler. The fire grate A may be similar to that already described and have lateral air passages K or hollow grate bars of known construction may be used. The fuel hoppers D' are arranged at either side

of the walls L of the generator, the refractory partitions F as before having air passages H, H', H². The water tube boiler 40 shown has a baffle M disposed above the fire grate and the first two rows of water tubes N, the products of combustion subsequently, after striking these tubes N, flowing around and between the remaining water tubes O as in the usual type of Babcock and Wilcox water tube steam generator.

What I claim as my invention and desire to secure by Letters Patent is:—

In a furnace for steam generators, the combination of a fire grate, a combustion chamber, fuel supply passages at opposite sides of the grate, a refractory partition forming one wall of each fuel passage and having therein two chambers, one situated close to the outer face of the partition and extending through the end wall of the furnace and the other situated between and communicating with both said air inlet chamber and the combustion chamber, whereby excessive heating of the wall of the fuel passage, formed by said partition will be prevented by the cool air within the inlet chamber and heated air will be supplied to the combustion chamber, and additional air supply conduits arranged to supply air to the fuel on either side of the grate.

In testimony whereof I have signed my name to this specification in the presence of two subscribing witnesses.

JACOB RAMACHER.
